UNITED STATES PATENT OFFICE.

LEE ROY SPOONER AND PAUL L. GRAY, OF WATERTOWN, SOUTH DAKOTA.

VENDING MACHINE.

Application filed March 21, 1923. Serial No. 626,607.

To all whom it may concern:

Be it known that we, LEE ROY SPOONER and PAUL L. GRAY, citizens of the United States, residing at Watertown, in the county 5 of Codington and State of South Dakota, have invented certain new and useful Improvements in Vending Machines, of which the following is a specification, reference being had to the accompanying drawings.

This invention relates to vending machines and more particularly to vending machines for elongated articles of substantially uniform diameter, such as pencils.

An important object of the invention is 15 to provide a rotatable article support for use in a vending machine of this character constructed to support a plurality of different types of the same class of article and to selectively align a selected type with an 20 ejector mechanism by means of which it may be expressed from a machine.

A further object of the invention is to provide a device of this character in which the articles to be vended may be readily inserted and by means of which the inserted articles are always maintained in position for ejection when aligned with the ejector.

A further object of the invention is to provide means for preventing an operation 30 of the machine when the aligned portion of the machine contains no article to be vended.

A still further object of the invention is to provide means for preventing theft of such articles through the opening through 35 which they are ejected by the plunger.

These and other objects we attain by the construction and arrangement shown in the accompanying drawings wherein for the purpose of illustration is shown a preferred 40 embodiment of our invention and wherein like reference characters designate like parts throughout.

In the drawings:—

Figure 1 is a front elevation of a vending 45 machine constructed in accordance with our invention;

Figure 2 is a vertical sectional view therethrough;

Figure 3 is an enlarged detailed sectional 50 view showing the operation of the ejector; and

Figure 4 is a fragmentary perspective of the rotatable support employed.

Referring now more particularly to the 55 drawings, the numeral 10 indicates a casing

divided by a central horizontal partition 11 into upper and lower compartments 12 and 13. In the upper compartment 12 is disposed a rotary support 14 for the articles to be vended and in the lower compartment is disposed any suitable coin release lock plunger mechanism such as generally indicated at 15. Through the front wall of the lower compartment 13 projects the end of a plunger 16 and this wall is provided at its 60 upper end with an opening 17 by means of which a coin for releasing the plunger may be inserted, the coin release mechanism not being herein specifically described, but being shown similar to that described and 65 claimed in our copending application, Serial No. 626,606, filed March 21, 1923, for coin release locks for vending machines.

The top, front and side walls of the upper compartment are preferably formed of 75 transparent material such as heavy glass, and the rear wall thereof embodies a hinged section formed in two pivotally connected portions 18 and 19. The upper section 19 may be thrown down to permit access to 80 the rotatable supporting member 16 hereinbefore referred to. In the lower section a shaft 20 has its rear end rotatably mounted, the front end thereof extending through a bearing 21 mounted in a cross bar 22 extending transversely of the front wall, the outer end of the shaft being provided with an operating knob 22 by means of which it may be operated. Between the front and rear walls of the section 12 the shaft 20 has mounted 85 thereon a pair of spaced discs 23, each rigidly secured to the shaft. Each of these discs is provided with a plurality of radially extending slots 24, the alternate slots 24 being short for a purpose presently to 90 appear.

Each disc is provided at its periphery with a flange 25, the flange 25 of the rear disc 23 having formed thereon or secured thereto a plurality of cam members 26 affording therebetween spaces 27, the rear face of these cams being in the form of a peak as indicated at 28. In the present instance we have illustrated certain of these cams as integrally formed and other of the cams as 105 applied to the flange 25 and secured thereto, the last named cams having an extended forward portion 29, the forward end of which is secured to the flange 25 of the forward disc 23 so that these discs are firmly 110

held in proper spaced relation and the peripheries of the discs rendered rigid one to the other.

When the discs are so secured the slots 5 of the discs align with one another, the long slots of one disc aligning with the long slots of the other. Through the slots of the front discs 23 bolts 30 are inserted, the heads 31 arranged forwardly, the rear ends of the 10 bolts being threaded and having applied thereto a retaining nut 32, the heads 31 and nuts 32 of the bolts being of greater size than the slots and accordingly maintaining the bolts against displacement by the slots. 15 These bolts will roll upon the walls of the slots 24 and accordingly will be arranged at the inner ends of the slots at the upper sides of the discs and at the lower ends of the slots at the lower sides of the discs provided 20 the slots are free from articles to be vend- ed. By inspecting Figure 1 of the draw- ings, the reason for forming certain of the slots shorter than the remaining slots will become obvious, the shortening of alternate 25 slots permitting passing of the heads of the bolts 30 and preventing interference with the bolt of one slot by the bolts of adjacent slots. At the same time it permits certain 30 of the slots to be extended for the greatest possible distance into the disc. In filling 35 the same with the articles to be vended, the upper section 19 of the rear wall is thrown down and the pencils or other articles are inserted through the slots of the discs 23 so that they rest upon the bolts 31, the upper 40 half of the discs being filled. When the shaft is rotated to place these filled slots to- 45 ward the bottom of the case, attention is called to the fact that as these filled slots approach the bottom the weight of the bolts 30 is placed upon the pencils in the slots and the pencils accordingly forced downwardly until they come in engagement with the inner faces of the flanges 25 at which time if the slot in which they repose be aligned with 50 the ejector mechanism they will be positioned for ejection.

The second half of the machine may then be filled and the machine placed in opera- 55 tion. The plunger 16 hereinbefore referred to has an upward extension 33 directed through a slot 34 formed in the partition 11. The upper end of this extension is pro- 60 vided with a guiding plunger 35 and an ar- ticle ejector 36. The guiding plunger 35 is adapted to engage the wheel at the outer 65 surface of the flange 25 of the rearmost disc 23 and by this engagement intermediate the cams 26 thereof to rotate the wheel suffi- 70 ciently to provide an exact alignment of the selected slots 24 containing selected articles between the discharge opening 37 of the front wall and the article ejector 36 as the plunger is moved forward and prior to the 75 engagement of the article ejector with the

article. Continued forward movement of the plunger results in the machine being moved forwardly so that its forward end is projected outwardly of the casing through the opening 37 where it may be removed by 70 the purchaser. If in the operation of the machine a slot from which all of the articles to be vended have been removed is aligned with the ejector 36, the ejector in its forward movement will engage in lieu 75 of the end of the article to be ejected the rear end of the bolt 30 occupying the slot, and since forward movement of this bolt will be prevented by the nut 32 thereof, movement of the plunger is prevented prior 80 to the time when the lock releasing coin by means of which the plunger has been re- leased for movement is positioned, so that the plunger may be released and the wheel rotated to bring a slot having an article 85 therein into alignment therewith.

From the foregoing it is believed to be obvious that by constructing our machine in accordance with the foregoing, means are provided whereby the articles are fed to 90 the proper position for ejection and for si- multaneously holding a great many different varieties of such articles. Means are also provided preventing loss of possible cus- tomers through failure of the machine to de- 95 liver an article. At the same time an ex- tremely simple and durable device is pro- vided and one which may be manufactured at a relatively low cost. It has often been noted that with machines of this type, the 100 articles carried by the machine are surrepti- tiously removed through the discharge open- 105 ing 37 thereof. In order to prevent such occurrence we provide about the outer end of this opening a truncated cone-shaped cap 38 having an opening in its outer end align- 110 ing with the opening 37 and having at its inner end a pair of springs 39 which yield outwardly to permit a passage of the vended article but which hold against inward 115 pressure and close the passage except dur- ing the discharge of a vended article.

What is claimed is:—

1. In a vending machine, a casing, a sup- port rotatable within the casing, the casing 115 having an opening formed in the wall there- of and being provided with an ejector shift- able toward and away from the opening, the lower portion of the periphery of the rotat- able support being arranged in the path of 120 the ejector, said support having radial mer- chandise slots formed therein selectively alignable with the ejector and opening, and means slidable in the slots forcing mer- chandise contained therein downwardly in the 125 selected slot to align with said ejector and limiting the movement of the ejector when the merchandise of the slot is exhausted.
2. In a vending machine, a casing, a sup- port rotatable within the casing, the cas- 130

ing having an opening formed in the wall thereof and being provided with an ejector shiftable toward and away from the opening, the lower portion of the periphery of the rotatable support being arranged in the path of the ejector, said support having radial merchandise slots formed therein selectively alignable with the ejector and opening, and means slideable in the slots forcing merchandise contained therein downwardly in the selected slot to align with said ejector and limiting the movement of the ejector when the merchandise of the slot is exhausted, comprising a member slideable in the slot and having at its ends enlargements abutting the end faces of the support.

3. In a vending machine, a casing, a support rotatable within the casing, the casing having an opening formed in the wall thereof and being provided with an ejector shiftable toward and away from the opening, the lower portion of the periphery of the rotatable support being arranged in the path of the ejector, said support having radial merchandise slots formed therein selectively alignable with the ejector and opening, and means slideable in the slots forcing merchandise contained therein downwardly in the selected slot to align with said plunger and limiting the movement of the plunger when the merchandise of the slot is exhausted, and means carried by the ejector engaging said support in advance of the ejector and accurately aligning the selected slot with the ejector.

4. In a vending machine, a casing, a support rotatable within the casing and including spaced discs having aligned radially extending slots formed therein, the casing having an opening formed in the wall thereof with which the outer ends of the slots are alignable, means exteriorly of the casing for rotating the support to align a selected slot with the opening, and members slideable in said slots having enlarged portions abutting remote faces of said discs and seeking the lower ends of said slots by gravity as the support is rotated.

5. In a vending machine, a casing, a support rotatable within the casing and including spaced discs having aligned radially extending slots formed therein, the casing having an opening formed in the wall thereof with which the outer ends of the slots are alignable, means exteriorly of the casing for rotating the support to align a selected slot with the opening, members slideable in said slots having enlarged portions abutting remote faces of said discs and seeking the lower ends of said slots by gravity as the support is rotated, and an ejector aligned with the opening and engaging the lowermost article contained in the slots of said discs aligned with the opening and pro-

jecting the same through the opening of the casing during its forward movement.

6. In a vending machine, a casing, a support rotatable within the casing and including spaced discs having aligned radially extending slots formed therein, the casing having an opening formed in the wall thereof with which the outer ends of the slots are alignable, means exteriorly of the casing for rotating the support to align a selected slot with the opening, members slideable in said slots having enlarged portions abutting remote faces of said discs and seeking the lower ends of said slots by gravity as the support is rotated, and an ejector aligned with the opening and engaging the lowermost article contained in the slots of said discs aligned with the opening and projecting the same through the opening of the casing during its forward movement, and means carried by the ejector and engaging the support in advance of the ejector accurately aligning a selected slot between the ejector and the opening.

7. A merchandise support for vending machines of the character described, comprising a shaft, spaced discs secured to the shaft, each provided with a peripheral flange, radial slots formed in said discs, and members slideable in said slots having portions abutting remote faces of the discs.

8. In a merchandise support for vending machines, a shaft, a pair of spaced discs carried by the shaft and having peripheral flanges, aligned radial slots formed in said disc, alternate slots having their inner ends further remote from the axis of the discs than the remaining slots, and bolts slideable in corresponding slots of the discs having their heads abutting the outer face of one disc and provided upon the opposite end with a nut abutting the outer face of the other disc.

9. In a merchandise support for vending machines, a shaft, a pair of spaced discs carried by the shaft and having peripheral flanges, aligned radial slots formed in said disc, alternate slots having their inner ends further remote from the axis of the discs than the remaining slots, and bolts slideable in corresponding slots of the discs having their heads abutting the outer face of one disc and provided upon the opposite end with a nut abutting the outer face of the other disc, and positioning cams attached to the flange of one of said discs.

10. In a merchandise support for vending machines, a shaft, a pair of spaced discs carried by the shaft and having peripheral flanges, aligned radial slots formed in said disc, alternate slots having their inner ends further remote from the axis of the discs than the remaining slots, and bolts slideable in corresponding slots of the discs having their heads abutting the outer face of one

disc and provided upon the opposite end with a nut abutting the outer face of the other disc, and positioning cams attached to the flange of one of said discs, certain of said cams being provided with extensions rigidly engaging the flange of the other disc.

11. In a vending machine, a casing, a support rotatable within the casing and including spaced discs having aligned radially extending slots formed therein, the casing having an opening formed in the wall thereof with which the outer ends of the slots are alignable, means exteriorly of the casing for rotating the support to align a selected slot with the opening, and members slidable in said slots having enlarged portions abutting remote faces of said discs and seeking the lower ends of said slots by gravity as the support is rotated, and a truncated cone-shaped member having its base abutting the outer surface of the casing about said opening and provided at its outer end with an opening aligning with the opening of the casing, and means within said member permitting passage of an article from the opening of the casing and preventing passage of an article from the opening of the outer end thereof.

12. In a vending machine, a casing, a support rotatable within the casing and including spaced discs having aligned radially extending slots formed therein, the casing having an opening formed in the wall thereof with which the outer ends of the slots are alignable, means exteriorly of the casing for rotating the support to align a selected slot with the opening, and members slid- able in said slots having enlarged portions abutting remote faces of said discs and seeking the lower ends of said slots by gravity as the support is rotated, and a truncated cone shaped member having its base abutting the outer surface of the casing about said opening and provided at its outer end with an opening aligning with the opening of the casing, and means within said member permitting passage of an article from the opening of the casing and preventing passage of an article from the opening of the outer end thereof, comprising a pair of springs yielding against pressure from within the casing and normally

overlying the opening of the casing to close the same.

13. A merchandise support for vending machines of the character described, comprising a shaft, spaced discs secured to the shaft, each provided with a peripheral flange, radial slots formed in said discs, members slidable in said slots having portions abutting remote faces of the discs, and positioning cams attached to the flange of one of said discs.

14. In a vending machine, a casing, a support rotatable within the casing, the casing having an opening formed in the wall thereof and being provided with an ejector shiftable toward and away from the opening, the lower portion of the periphery of the rotatable support being arranged in the path of the ejector, said support having radial merchandise slots formed therein selectively alignable with the ejector and opening, means slidable in the slots forcing merchandise contained therein downwardly in the selected slot to align with said ejector and limiting movement of the ejector when the merchandise of the slot is exhausted, and coacting means upon said ejector and support for accurately aligning a selected slot between the ejector and said opening.

15. A merchandise support for vending machines of the character described, comprising a shaft, spaced discs secured to the shaft, each provided with a peripheral flange, radial slots formed in said discs, members slidable in said slots having portions abutting remote faces of the discs, and positioning cams attached to the flange of one of said discs, certain of said cams being provided with extensions rigidly engaging the flange of the other disk.

16. A merchandise support for vending machines of the character described, comprising a shaft, spaced discs secured to the shaft, aligned radial slots formed in said discs, and means associated with the discs for shifting merchandise within the slots toward the outer ends of the slots when the merchandise in the slot is beneath the shaft.

In testimony whereof we hereunto affix our signatures.

LEE ROY SPOONER.
PAUL L. GRAY.
